UNITED STATES PATENT OFFICE

148,811

DESIGN FOR A COSMETIC BAG OR SIMILAR ARTICLE

Lilyan Malmstead, New York, N. Y.

Application December 23, 1946, Serial No. 135,700

Term of patent 7 years

(Cl. D87—3)

To all whom it may concern:

Be it known that I, Lilyan Malmstead, a citizen of the United States of America, residing in New York city, county of New York, and State of New York, have invented a new, original, and ornamental Design for a Cosmetic Bag or Similar Article, of which the following is a specification, reference being had to the accompanying drawing, forming part thereof, wherein,

I claim:

The ornamental design for a cosmetic bag or similar article, substantially as shown.

LILYAN MALMSTEAD.
